UNITED STATES PATENT OFFICE.

REINHOLD J. REIM, OF HAYWARD, CALIFORNIA, ASSIGNOR OF ONE-HALF TO FRANZ XAVER JAEGEL, OF HAYWARD, CALIFORNIA.

SHOE.

Application filed February 8, 1922. Serial No. 535,099.

To all whom it may concern:

Be it known that I, REINHOLD J. REIM, a citizen of the United States, residing at Hayward, in the county of Alameda and State of California, have invented certain new and useful Improvements in Shoes, of which the following is a specification.

My invention is an improved blucher shoe constructed in such manner as to reinforce the point of connection of the lower ends of the eyelet members of the quarter with the vamp.

Referring to the annexed drawings in which my invention is illustrated and which forms a part of this specification:

Figure 1 is a side view of a blucher shoe constructed in accordance with my invention.

Figure 2 is a front view of the upper of a blucher shoe constructed in accordance with my invention.

Figure 3 is an underside view of the upper shown in Figure 2.

Figure 4 is a side view of the quarter of a blucher shoe made in accordance with my invention.

Figure 5 is a plan of the vamp of a blucher shoe made in accordance with my invention.

Figure 6 is a plan view of the counter lining of a blucher shoe constructed in accordance with my invention.

In the drawings 1 indicates the vamp and 2 the quarter of a blucher shoe. The vamp is formed with the usual central projecting member 3 at its upper edge and with upper edges 4 which incline upwardly in an outward direction from the base of said member

3. This member may be elongated into a tongue if desired. Notches 5 are cut downwardly in the vamp at the junctures of the base of the member 3 and the edges 4. The quarter 2 is formed with the usual eyelet members 6 for the lacing and the forward edges 7 which are inclined rearward in a downward direction. The counter lining 8 is formed with tongues 9 at its upper corners.

The quarter and the vamp are put together with the lower ends of the eyelet members 6 extending into the notches 5 and the rear vamp edges 4 fitting over the forward edges 7 of the quarter, while the

counter lining 8 is placed in the quarter with the ends of the lining under the forward ends of the quarter and the tongues 9 also under said quarter ends and under the notches 5. The tongue 10 of the shoe is placed under the member 3. The rear edges 4 of the vamp are sewed to and over the forward edges of the quarter and to the forward ends of the counter lining 8 by stitching 11. The lowermost points of the ends of the eyelet members 6, the vamp and the counter lining tongues 9 are sewed together by stitching 12 which extends around the edges of said notches and around the edge of the vamp member 3 and through the shoe tongue 10 and around the rear of the quarter in a continuous seam, thus sewing the tongue to said member and securing the lining to the quarter. The sewing of the lowermost points of the eyelet members 6 within the notches 5 and to the tongues 9 reinforces the points of connection of said members and the vamp and prevents tearing of the quarter or the vamp at said points. Moreover the tongues 9 make a smooth joint under the connecting points of the eyelet members and the vamp, thus preventing chafing of the feet at said points.

Having described my invention, I claim:

1. In a blucher shoe, a vamp, quarters having eyelet members, the vamp being provided with a pair of notches in its upper edge into which extend the lowermost points of the eyelet members, and a counter lining formed with tongues on its upper forward corners, said eyelet members, said vamp, and said tongues being sewed together around said notches.

2. In a blucher shoe, a vamp, quarters having eyelet members, the vamp being provided with a pair of notches in its upper edge into which extend the lowermost points of the eyelet members, and a counter lining formed with tongues on its upper forward corners, said eyelet members, said vamp, and said tongues being sewed together around said notches, the upper edges of said vamp extending over the forward edges of the quarter, and the edges of the quarter and the vamp, and the counter lining being sewed together.

In testimony whereof I affix my signature,
REINHOLD J. REIM.
